(57) CLAIM

The ornamental design for a lacrosse head, as shown and described.

DESCRIPTION

FIG. 1 is a perspective view from above illustrating the back and right side of an exemplary embodiment of a lacrosse head;

FIG. 2 is a back view of the lacrosse head of FIG. 1;

FIG. 3 is a front view of the lacrosse head of FIG. 1;

FIG. 4 is a left side view of the lacrosse head of FIG. 1;

FIG. 5 is a right side view of the lacrosse head of FIG. 1;

FIG. 6 is a bottom view of the lacrosse head of FIG. 1; and,

FIG. 7 is a top view of the lacrosse head of FIG. 1.

Where applicable, elements are shown in broken lines herein for illustrative purposes only, and form no part of the claimed design.

1 Claim, 7 Drawing Sheets
